8 Claims. (Cl. 123—69)

This invention relates to an inexpensive gaseous fuel burning internal combustion engine, and more particularly relates to a small inexpensive but efficient gas burning two-cycle internal combustion engine having an improved fuel injection system which introduces the gaseous fuel after the engine ports are closed and eliminates loss of fuel with the exhaust as normally occurs in two-cycle engines. The engines of this invention preferably have a pressure lubricating system controlled by engine crankcase pressure.

With the increasing availability of gaseous type fuels, such propane, together with the increasing acceptance and use of the fuel injection principle of fuel feeding for automotive engines, there is now a need for low-cost efficient operating gas burning internal combustion engines using a simplified fuel injection system and regulating device for feeding the gaseous fuel to the engine in such a manner that the burned fuel will not be lost with the exhaust gases.

This invention now provides small engines, fed from capsules or bottles of propane or other gas-type fuel. The small engines of this invention are light in weight, low in cost, easy to start and are especially useful for lawnmowers, portable tools and the like.

Conventional two-cycle engines receive fuel during the exhaust stroke and lose much unburned fuel. Such engines cannot run for reasonable lengths of time on small bottles or tanks of gaseous fuel. They are thus unfit for lawnmower or power tool power plants. On the other hand, the two-cycle engines of the present invention have the exhaust scavenged therefrom and the new air supply introduced and even compressed before the fuel is introduced. Therefore, no unburned fuel is lost, and efficiencies comparable with heavier, more expensive four-cycle type engines are obtained.

The two-cycle engines of this invention utilize a ported cylinder and pressurized crankcase for supplying an air-charge to the combustion chamber and for removing exhausted combustion products therefrom. The ignition system for the engine may be either in the form of a spark plug, a glow plug, or a compression-ignition diesel type cycle. The engines are equipped with a simple, easily mass-produced gaseous fuel injection device which introduces the gas fuel into the engine combustion chamber after the engine ports are closed and supplies the correct fuel-air ratio to the engine throughout normal changes in barometric pressure and air density to thereby develop maximum engine efficiency and power and to prevent engine overspeed.

The fuel injection devices of the engines of this invention generally include a bore in the engine block receiving a reciprocable metering rod and a check valve defining a fuel chamber therebetween. A regulated supply of pressurized gaseous fuel from a high-pressure reservoir or storage source is fed to this fuel chamber before being injected into the engine. The metering rod forms an end wall for the fuel chamber and rides on the engine

2

crankshaft cam. The cam lifts the rod to compress the fuel charge which is then injected into the engine. The check valve is backed by a spring and serves as a gate permitting the fuel charge to flow into the combustion chamber. Injection of each fuel charge is timed to correspond with the compression stroke of the engine through proper positioning of the crankshaft cam lobe and the fuel volume is regulated to the desired air-fuel ratio supplied to the combustion chamber.

10 It is, therefore, an object of this invention to provide a low-cost, efficient gaseous fuel burning internal combustion engine.

Another object of this invention is to provide a two-cycle gaseous fuel burning internal combustion engine having an easily mass produced fuel injection system for supplying a fuel charge to the engine combustion chamber only after the ports of the chamber are closed.

20 A still further object of the present invention is to provide a fuel injection system for an internal combustion engine that is capable of maintaining an optimum fuel-air ratio feed to the engine while operating throughout normal changes in barometric pressure and air density.

25 A still further object of this invention is to provide a fuel injection system for a gaseous fuel burning two-cycle internal combustion engine that will regulate the quantity of fuel delivered to the engine in proportion to the weight of the air charge entering the engine combustion chamber, to thereby maintain an optimum fuel-air ratio of the combustion mixture entering the combustion chamber.

30 A still further object of this invention is to provide a two-cycle gaseous fuel burning engine with a built-in fuel injection system which delivers optimum amounts of fuel to the combustion chamber throughout the normal operating range of the engine and will deliver excessive amounts of fuel beyond a certain designed operating engine speed, to purposely induce a loss in efficiency of the engine and thereby prevent development of overspeed conditions.

35 Other and further objects of this invention will be apparent to those skilled in this art from the following detailed description of the annexed sheet of drawings which forms a part of this specification.

40 45 In the drawings:

Figure 1 is a somewhat diagrammatic vertical cross-sectional view, with parts in elevation, of a two-cycle engine according to this invention showing the position of the parts at the beginning of the engine compression stroke;

Figure 2 is a view similar to Figure 1, but showing the position of the parts at the completion of the compression stroke; and

50 55 Figure 3 is a schematic view of a pressure regulator valve for the engine fuel injection device.

As shown on the drawings:

60 The engine assembly 10 of Figures 1 and 2 includes a single cylinder, two-cycle internal combustion engine E, a fuel injection assembly F, and a fuel pressure control assembly V, as better shown in Figure 3. The fuel injection assembly F is illustrated as integrally formed in the body of the engine E, but it should be understood that this assembly could be housed outside of the engine body, if so desired. It should also be understood that the engines of this invention could be of the multiple cylinder type.

65 70 75 The two-cycle, single cylinder engine E, as shown, includes a cylinder block 11, a cylinder head 12, a crankcase 13, and a crankshaft boss 14. These portions of the engine body can be formed in one piece or as separate pieces.

A crankshaft 15 is supported by the boss 14.

The cylinder block 11 is formed with a sleeve bore 16, a fuel injection system bore 17, and a crankcase chamber bore 18. The bore 18, together with the crankcase member 13, defines a crankcase chamber 19 for the engine. This chamber 19 is subjected to air pressure as a function of air density and engine speed, which pressure is utilized for a purpose and function that is more fully described hereinafter.

The cylinder bore 16 has a hardened, wear-resisting, cylinder sleeve 20 pressed therein. An exhaust port 21 is provided through the sleeve and engine body about midway between the ends of the sleeve. An inlet port 22 is provided through the sleeve at a level that partially overlaps the port 21. This port 22 is connected through a passage 22a with the crankcase chamber 19 as shown. A third port 23 is provided through the sleeve at a level below the ports 21 and 22 to vent the crankcase chamber 19 with the atmosphere when the piston uncovers the port as shown in Figure 2, thereby supplying air to the crankcase chamber underneath the piston.

A domed piston 24 is slidably mounted in the sleeve 20 and is connected through a connecting rod 26 to the journal 27 of a crank pin 28 on the crankshaft 15. The crankshaft 15 includes a counterweight portion 29, a cam lobe 30, an oil groove 31 and a delivery shaft portion 32. The crankshaft 15 also includes an oil groove 33 that supplies lubricant from the groove 31 to the crankpin journal 27.

The crankshaft boss 14 of the block 11 and crankcase portion 13 is appropriately bored at 34 to receive a crankshaft bushing 35 which journals the crankshaft 28. The crankcase member 13 and the bushing 35 have registering bores 36 and 37 therethrough to form a lubricant passage for supplying lubricant to the groove 31.

The cylinder head 12 is air cooled and provided with fins 38. The glow plug S is threaded into a threaded bore 39 of the head 12.

A combustion chamber 40 is provided between the head of the piston 24 and the cylinder head 12.

When the piston 24 reaches the top of its stroke, as shown in Figure 2, the crankcase port 23 is uncovered and air can enter the crankcase chamber 19. Then when the piston is forced downwardly on the power stroke, the port 23 is closed and the air in the crankcase chamber 19 is compressed. As the piston continues its downward stroke, the exhaust port 21 is opened and the exhaust gases are scavenged out of the combustion chamber 40. While the exhaust chamber is still opened, the inlet port 22 is uncovered by the piston and compressed air from the crankcase 19 flows through the passage 22a and port 22 into the combustion chamber. A portion of this air is used to scavenge the remainder of the exhaust gases from the combustion chamber through the port 21, and then on the succeeding upstroke of the piston, both ports 22 and 21 are closed so that a portion of the air from the crankcase is trapped in the combustion chamber 40 and compressed by the piston.

In the conventional two-cycle engine, fuel would be introduced with the air through the inlet port 22.

The engines of the present invention, however, receive fuel from the fuel injection system F when the piston is at or near the top of its stroke.

The fuel injection system F includes a reciprocal metering rod 41, a check valve 42, a fuel chamber 43 between the end faces of the metering rod 41 and check valve 42, an orificed fuel metering passage 44 adjoining the chamber 43 with the combustion chamber 40, and a fuel feed passage 46 to the fuel chamber 43.

The metering rod 41 has a spring retaining pad portion 47 riding on the cam lobe 30 of the crankshaft 15. A coil spring 48 bottomed on a counterbore shoulder 49 in the cylinder block 11 maintains the metering rod 41 against the cam lobe 30.

The bore 17 slidably supporting the metering rod 41

is counterbored at 50 to an enlarged diameter for slidably receiving the check valve 42 and for providing a bottoming shoulder 51 for the check valve. A coil spring 52 is provided to seat the check valve 42 on the shoulder 51. The metering passage 44 is closed by the check valve 42 when it is bottomed on the shoulder 51.

The cylinder head 12 has a bore 53 therein forming a retaining recess for the coil spring 52 to bottom the spring and maintain a predetermined load thereon. A fuel pressure regulating valve assembly V shown in Figure 3 is provided to feed the correct quantity of fuel to the injection chamber 43. This assembly includes a housing 54 carrying a slidable needle valve 55 with a shaft portion 56 that is connected for differential movement to the diaphragms of a pair of series arranged units 57 and 58.

The valve housing 54 has a seat 59 controlled by the needle valve 55 for selectively joining a conduit 60 from the gas bottle or receptacle R with a conduit 61 connected to the feed line 46 to the chamber 43.

Each unit 57 and 58 includes a flexible diaphragm 62 dividing the units into two compartments. One side of each diaphragm is vented to the atmosphere through a vent 63. The two adjacent compartments of the units are respectively joined through a conduit 64 with the inlet passage 46 and through a conduit 66 with a port 67 in the crankcase chamber 19.

It will be noted that the diaphragm of unit 58 is larger than the diaphragm of unit 57. The larger diaphragm is activated by crankcase pressure in a direction to open the needle valve 55. The smaller diaphragm of unit 57 is actuated by pressure in the fuel line 61 and 46 in a direction to close the needle valve. Therefore, the position of the needle valve will be determined by the relative pressures existing in the fuel supply line and the crankcase. As crankcase pressure increases and as fuel pressure decreases the needle valve will open. By varying the areas of the respective diaphragms 62, the extent and ratio of movement of the needle valve 55 and the corresponding reduction or increase in fuel volume entering the inlet passage 46 will be varied. A proper fuel-air ratio is thereby automatically obtained.

The reservoir or gaseous fuel bottle R can be of the replaceable commercially available type charged with fuel at a desired maximum pressure.

Lubrication is provided from a chamber in the bottom of the crankcase 13. As shown an extension 68 on the crankcase member 13 provides an oil sump or chamber 69 which is closed by a bottom cap 70 and communicates with the crankcase chamber 19 through a passageway 71 controlled by a valve 72 urged by spring 73 in a direction to close the passageway 71. The oil sump is connected through the passageway 36 to the lubrication groove 31.

Lubricant draining to the bottom of the crankcase chamber 19 is returned to the sump 69 when the pressure in the crankcase chamber is sufficient to overcome the spring load on the valve 72 thereby opening the valve. The valve will close before the crankcase chamber is vented to the atmosphere so that the sump will remain under pressure and provide a source of pressurized lubricant for the engine journals.

From the above description it should be understood that gaseous fuel from the reservoir is introduced into the metering chamber 43 under the control of the needle valve 55 which valve is regulated by crankcase pressure and gaseous fuel pressure. On the upstroke of the piston after the ports 21 and 22 have been closed and preferably as the piston is at or approaches the top of its stroke, the cam lobe 30 raises the metering rod 41 to block off the passageway 46 and to compress the charge of gas in the chamber 43 against the check valve 42. When the pressure in this chamber 43 reaches a magnitude sufficient to overcome the spring load on the check valve 42,

the valve is opened and the charge of gas is forced through the passage 44 into the combustion chamber above the piston. The gaseous fuel is thus injected into the combustion chamber at relatively high pressures depending upon the load on the check valve 42 and the amount of the fuel injected is controlled by a predetermined ratio of crankcase pressure and fuel pressure.

On ignition of the fuel and air mixture in the combustion chamber, the piston 24 starts downwardly on its power stroke and closes off the crankcase port 23 thereby increasing the pressure in the crankcase chamber 19 and tending to open the needle valve 55. The degree in which the valve 55 opens will depend on the pressure existing in the feed line 46 and the extent of the pressure build up in the crankcase 19. A reduction in crankcase pressure reduces the weight of air fed to the combustion chamber, and less fuel is then required to maintain a desired fuel-air ratio. Preferably, the ratio of area of diaphragm 62 in unit 57 to area of diaphragm 62 of unit 58 is proportioned to the ratio of pressure in crankcase chamber 19 to fuel supply pressure in line 46. Then fuel supply pressure becomes a function of crankcase pressure. The needle valve 55 will close when the piston begins its upward or compression stroke which thereby reduces the crankcase pressure.

By a choice of metering orifices the injection system can be designed to enrich the mixture as engine speed increases, thereby controlling maximum speed of the engine without varying the setting of valve V on the fuel bottle.

No ignition system is needed for the engine since the glow plug S is ample for efficient operation.

I claim as my invention:

1. A gas engine which comprises a first cylinder, a piston slidably mounted in said first cylinder, a crankshaft driven by said piston, a cam on said crankshaft, a second cylinder, a plunger slidably in said second cylinder driven by said cam, means for feeding gas fuel to said second cylinder, said plunger being effective to pump gas in said second cylinder into the first cylinder, and a valve controlled by pressure under said piston to regulate flow of gas fuel into said second cylinder.

2. In an internal combustion engine of the two-cycle type having a pressurized crankcase, the improvements which comprise a gas fuel injection system for said engine including a source of gas fuel under pressure, a valve for metering fuel from said source, and means actuated by pressure in the crankcase and by pressure in said source for controlling said valve.

3. A gas burning two-cycle engine comprising a block assembly providing a combustion chamber and a crankcase chamber, a piston slidable in the block assembly separating the combustion and crankcase chambers, a crankshaft in the crankcase chamber driven by said piston, an air inlet port for the crankcase chamber, an air inlet port for the combustion chamber receiving air from the crankcase, an exhaust port for the combustion chamber, said piston controlling said ports to draw air into the crankcase chamber, to force air from said crankcase chamber into the combustion chamber and to exhaust spent gases of combustion and some air from the combustion chamber, an engine driven fuel injection device forcing fuel into the combustion chamber when the piston is at the top of its stroke and said combustion chamber ports are closed, and a fuel metering valve controlled by

crankcase air pressure to regulate fuel flow to the injection device.

4. In a gaseous fuel burning internal combustion engine of the two-cycle type that includes a piston reciprocal in a cylinder, a crankshaft, a connecting rod connecting said piston to said crankshaft, and a closed crankcase; a fuel injection system for admitting a charge of pressurized fuel into said cylinder during the compression stroke of said engine comprising, means defining a gaseous fuel receiving chamber for delivery to an engine cylinder, means for compressing gaseous fuel in said fuel chamber, and a pressure regulated valve receiving high pressure gaseous fuel from a reservoir of said fuel and connected to deliver to said fuel chamber, said valve having a movable tapered plug portion and a shaft portion, and having means defining a pair of compartments each divided by the diaphragm of different sizes subjected on opposite sides to fuel chamber pressure and crankcase pressure respectively, said shaft connected to said diaphragm for differentially controlling the travel of the movable plug portion of said regulator valve.

5. The method of operating an internal combustion two-cycle engine on a gaseous fuel comprising metering gaseous fuel at a pressure which is a function of the pressure in the engine crankcase and a function of the fuel source, and forcing the fuel at said metered pressure into the combustion chamber on the compression stroke of the piston after the piston has passed the intake and exhaust ports.

30 6. The method of operating a two-cycle internal combustion engine on a pressurized gaseous fuel in a container which comprises measuring the pressure of the fuel in the container and the pressure of the crankcase, metering a fixed volume of fuel to the combustion chamber for each stroke of the engine at a pressure which is in inverse proportion to the pressure of the fuel in a container and in direct proportion to the crankcase pressure of the engine.

7. In a gas burning piston engine having a cylinder 40 and a piston reciprocal therein, a crankcase pressurized by the piston, an engine driven fuel injection device connected to deliver to the cylinder, and a pressure responsive fuel metering device connected to be controlled by engine crankcase pressure and connected to deliver to 45 said injection device.

8. In an internal combustion engine of the two-cycle type the improvements which comprise a gas fuel injection system for said engine including a source of gas fuel under pressure, an engine driven fuel injection device connected to deliver to a cylinder of the engine, and a pressure responsive fuel metering device connected to be controlled by the pressure of said pressure fuel source and connected to deliver fuel to said injection device.
